UNITED STATES PATENT OFFICE.

ADOLPH RUBIN, OF ST. LOUIS, MISSOURI, ASSIGNOR TO SIEBER PRODUCTS MANUFACTURING COMPANY, OF ST. LOUIS, MISSOURI, A CORPORATION OF MISSOURI.

KEEPER FOR REFRIGERATOR LOCKS.

Application filed July 11, 1923. Serial No. 650,837.

To all whom it may concern:

Be it known that I, ADOLPH RUBIN, a citizen of the United States, residing at St. Louis, Missouri, have invented a certain new and useful Improvement in Keepers for Refrigerator Locks, of which the following is a full, clear, and exact description, such as will enable others skilled in the art to which it appertains to make and use the same.

10 This invention relates to locks of the kind that are used on ice boxes and refrigerators.

Locks of the kind referred to comprise a movable latch, usually mounted on the door of the refrigerator, and a stationary keeper mounted on the front side of the refrigerator in such a manner that it will co-operate with the latch to retain the door in its closed position. In the conventional refrigerator lock the part of the keeper that co-operates with the latch is integrally connected to a plate which is secured by screws or other suitable fastening devices to the front of the refrigerator. Consequently, when the latch or the part of the keeper with which it co-operates becomes worn, or when the gasket at the edge of the door opening becomes worn, the door of the refrigerator will not fit perfectly tight when it is in its closed position, because the pressure of the latch on the keeper is depended upon to hold the door pressed tightly against the gasket. Moreover, as the latch is mounted on the front side of the door, it is necessary to use a keeper provided with a long shank when the door is of considerable thickness, and a keeper provided with a short shank when the door of the refrigerator is comparatively thin.

One object of my invention is to provide a 40 novel keeper for refrigerator locks that can be adjusted to compensate for wear on the latch of the lock or on the portion of the keeper with which the latch co-operates, or to compensate for wear on the door gasket.

45 Another object is to provide a novel keeper for refrigerator locks that can be adjusted easily to adapt it to refrigerator doors of different thicknesses.

Figure 1 of the drawings is a front elevational view of a refrigerator lock keeper constructed in accordance with my invention.

Figure 2 is a side elevational view of said keeper; and

55 Figure 3 is a side elevational view, show-

ing said keeper mounted in operative position on a refrigerator equipped with a lock provided with a latch that does not strike against the keeper during the operation of closing the door of the refrigerator.

Referring to the drawings, A designates a plate that is adapted to be secured to the front of a refrigerator by screws or other suitable fastening devices that pass through holes 1 in said plate. B designates a horizontally-disposed shank that projects forwardly from the plate A and C designates a latch-engaging member adjustably mounted on said shank B. The particular design of the member C is immaterial, and any suitable means can be used for retaining said member in adjusted position on the shank B. In the form of my invention herein illustrated the latch engaging member C has a notch or recess 2 that receives the latch of the lock when the refrigerator door is in its closed position, and said member is provided with a depending portion 3 that projects downwardly along one side of the shank B and also a horizontally-disposed portion 4 that projects laterally under the bottom edge of said shank, said parts 3 and 4 co-operating with the portion of the member C that bears upon the top edge of the shank B to form a yoke that embraces three sides of said shank. A clamping screw D that extends through a hole in the depending portion 3 of the member C and an elongated slot 5 in the shank B is threaded into a clamping plate E arranged on the other side 70 of the shank B in parallel relation to the portion 3, said screw being adapted to be tightened so as to draw the clamping plate E and the portion 3 tightly against the shank B.

If the latch or the portion of the keeper with which it co-operates becomes worn, or if the door gasket becomes worn, the clamping screw D can be released so as to permit the member C to be adjusted longitudinally of the shank B in a direction to compensate for wear, thus insuring the latch of the lock bearing against the keeper in such a way as to hold the door pressed tightly against the gasket on the front of the refrigerator when the door is in its closed position, it being of course understood that the clamping screw D is tightened after the member C has been adjusted in proper position on the shank. If the 100 105 110

keeper is to be used on a refrigerator provided with a comparatively thick door, the member C can be adjusted outwardly or towards the front end of the shank B, and if the keeper is to be used on a comparatively thin door, said member C can be adjusted inwardly or towards the plate A. It will thus be seen that a refrigerator lock keeper of the construction above described overcomes the necessity of a refrigerator manufacturer keeping in stock a number of different kinds or sizes of keepers.

The keeper herein illustrated is designed for use with a refrigerator lock of the type described in my pending application for patent for a refrigerator lock, Serial No. 607,723, filed December 18, 1922, which lock comprises a latch constructed in such a way that it will not strike against the keeper during the operation of closing the door of the refrigerator. In Figure 3 of the drawings I have illustrated such a lock, the reference character F designating the latch of the lock which is retained in an elevated position by a spring-actuated trigger while the refrigerator door is moving into its closed position, and the reference character G designating a tripping device that strikes against an abutment, and thus causes the latch to be released at about the time the door reaches its fully closed position. The abutment with which the tripping device G co-operates is preferably formed by a part H that projects laterally from the member C of the keeper, as shown in Figure 1, said abutment H being integrally connected to the member C so that the position of same will be changed when the latch-engaging member is adjusted longitudinally of the shank B. If desired, the plate A which carries the shank B may be provided at one edge with a notch or cut out portion 6, so as to receive

the part of the abutment H adjacent the member C, when said member is adjusted in its extreme inner position.

Having thus described my invention, what I claim as new and desire to secure by Letters Patent is:

1. A keeper for refrigerator locks, comprising a part adapted to be connected to the refrigerator and provided with a forwardly-projecting shank, and a latch-engaging member adjustably mounted on said shank and provided with a laterally-projecting abutment that is adapted to be engaged by a tripping device.

2. A keeper for refrigerator locks, comprising an attaching plate, a horizontally-disposed shank integrally connected to and projecting forwardly from said plate, a latch-engaging member provided with a substantially yoke-shaped portion that embraces said shank, a clamping plate bearing against said shank and movable with said yoke-shaped portion, and a retaining screw projecting through said yoke-shaped portion and shank and tapped into said clamping plate.

3. A keeper for refrigerator locks provided with a latch-engaging member that can be adjusted towards and away from the front of the refrigerator, and a laterally projecting abutment for a tripping device carried by said member, and adjustable with same.

4. A keeper for refrigerator locks, comprising a plate provided with a forwardly-projecting shank, an adjustable latch-engaging member mounted on said shank, a laterally-projecting abutment integrally connected to said member, and a notch or cut-out portion in said plate for receiving said abutment when said latch-engaging member is adjusted in its extreme inner position.

ADOLPH RUBIN.
